(57) **CLAIM**

The ornamental design for a pager with pill dispensing means, as shown and described.

DESCRIPTION

FIG. 1 is a perspective view of a pager with pill dispensing means in full lines with pills shown in broken lines representing environmental association matter being for illustrative purposes only and forming no part of the claimed invention.

FIG. 2 is a rear elevational view of the pager with pill dispensing means.

FIG. 3 is a front elevational view thereof.

FIG. 4 is a right side elevational view thereof, the left side elevational view being a mirror image of the right side view.

FIG. 5 is a top plan view thereof; and,

FIG. 6 is a bottom plan view thereof.
